SPRAYING NOZZLE

Theodore H. Nakken, New York, N. Y., assignor
to Nakken Products and Development Co., Inc.,
a corporation of Delaware

Application October 11, 1947, Serial No. 779,397

3 Claims. (Cl. 299—141)

1

This invention relates to improvements in spraying nozzles, and is directed, more particularly, to spray nozzles for various classes of services, and has as a principal object:

The provision of spray nozzles with any desired number of spraying openings of any desired size and shape.

A further object of the invention is the provision of a spray nozzle of the character described in which the fabrication of the nozzles themselves, and particularly the spraying openings, may be fabricated at extremely low cost.

Another object of the invention is the provision of a spray nozzle in which the interior content of the liquid to be sprayed is a minimum.

Yet another object of the invention is the provision of a spray nozzle which will atomize the liquid to be sprayed in a manner more efficiently than nozzles of the prior art.

Other objects and advantages of the invention will be apparent to those skilled in the art upon a study of the following specifications, and the accompanying drawings.

Referring to the drawings which are given by way of example to illustrate the invention:

Figure 1 is a sectional elevation of a nozzle made according to the invention;

Figure 2 is a sectional elevation of a modification of the nozzle shown in Figure 1;

Figure 3 is a fragmentary detailed view of the nozzle per se, of the form of the invention shown in Figure 1;

Figure 4 is a modified detailed view of certain parts shown in the nozzle of Figure 1;

Figure 5 is a plan view of the nozzle per se, shown in Figure 1; and

Figure 6 is a plan view of a modification of the nozzle shown in Figure 1.

Referring now to Figure 1, the main nozzle body 11 is preferably turned from hexagonal stock. It has a portion 12 which is hexagonal in form, a portion 13 extending upwardly, as seen in Figure 1, of the spray nozzle, and a threaded portion 14 extending downwardly. Extending through the body is a hole 15 the upper end portion 16 of which is stepped inwardly and internally threaded. Extending downwardly from the top, and communicating with the threaded hole 16, is a threaded hole 17 which is larger in diameter than the threaded hole 16.

The lower end of the body 11 has a convex portion 18, and formed centrally in the convex portion 18 is a seat 19, the sides of which are

angular with respect to the central hole 15. The hole 15, where it communicates with the seat 19, may be enlarged to form an annular chamber 20 therein adjacent to or communicating with the seat 19. The purpose of this annular chamber is to uniformly supply the liquid to be sprayed to spray openings which are arranged radially adjacent thereto. These openings will presently be described, and although the annular chamber is herein described as formed in the main body 11, it will be understood that I also contemplate forming an annular groove upon the shank of a member to be presently described which fits in the bore 15, and which has a head which seats on the seat 19. In other words, this annular chamber may be formed either in the body itself or upon the member which fits in the body because the performance will be substantially the same in either event.

A screw 21 has a long, smooth shank 22, which is co-extensive with the bore 15 and the annular chamber 20. It also has a threaded end 23 which engages the threads of the threaded hole 16. In order that the screw, once it is screwed into position, shall not become loosened, even under severe conditions of vibration or the like, I provide a slot 24 in the screw threaded portion 23 so that after the screw has been forced into position the threaded portion may be expanded. It is obvious that the screw may be locked in place by other means. On the lower end of the screw is provided a head 25 which is formed in such a manner that the angular surface 26 thereof rests solidly on the seat 19 formed in the body when the screw is tightly driven home.

The conical surface 26 of the screw may be indented with slot-like, triangular, square, or rounded indentations 27. In order to allow liquids to pass through the center bore 15, which contains the shank 22, of the screw 21, various means may be employed. The shank may be of such diameter as to substantially fill the bore 15, or it may be of such diameter that an annular space is left between it and the interior wall of the bore 15 for the passage of liquids. However, one preferred way of doing this is to form a helical channel 28 in the body 22 of the screw. This extends from the slot 24 to the base of the head 25 of the screw. This channel may be V-shaped in cross-section, and it may, instead of being in the form of a helix, be longitudinal, depending upon the physical size of the channel and the length of the bore 15.

When liquid under pressure is forced from the top of the nozzle through the bore (if clearance space is provided between it and the screw body 22), or via the helical or straight channel 28, it reaches the annular chamber 20 and thence it will be sprayed with great force out of the indentations 27 which form spray apertures. The slope of the indentations and their number will determine the spray pattern obtained, and the higher the pressure exerted upon the liquid, the higher will be the velocity of the liquid through these apertures.

It will be evident that the indentations may be kept very small, and they may be large in number; in fact, they may be so near together as to be separated only by very narrow lands.

These indentations may be made by means of a suitable tool under hydraulic pressure, for example, and thus they can be made so fine that the cross-sections of the separate spray holes are very small and they will offer higher resistance to the passage of the liquid and, consequently, this frictional resistance tends to promote the efficient shredding and atomization of the liquid being sprayed and at the same time the total friction will necessitate a high spraying pressure in order to pass the liquid through at a high velocity.

Instead of fabricating the channels or indentations 27 upon the conical surface of the screw head I may, instead, fabricate these indentations in the conical seat 19 of the nozzle proper, for example, in the manner shown in Figures 3 and 4, where the conical seat 19a has indentations 27a formed therein. Where this arrangement is used the head of the screw will be plain without any indentations.

As a further modification, I contemplate forming indentations both on the seat 19 of the valve body and also on the slanting head 26 of the screw in which event the screw would preferably be so set that the indentations on its head are interposed between the indentations formed on the seat 19.

In the modification shown in Figure 2, the body 11a has an hexagonal portion 12a, a shank portion 13a, and a threaded portion 14a for mounting the same. The device has a bore 15a, a stepped-in threaded portion 16a, and an enlarged internally threaded portion 17a. The screw shank 22a has an upper threaded portion 23a with a slot 24a formed therein for locking the screw in position in the body 11a.

Spaced apart from the lower end thereof the shank has an annular groove 20a which corresponds to the annular chamber 20 shown in Figure 1. Below the annular groove 20a and extending to the lower end thereof, the shank member 22a has a series of grooves or indentations 27a formed therein which correspond to the indentations 27 or 27a above described. The shank 22a may also have a helical channel 28a formed therein and communicating with the threaded portion 17a, and communicating with the annular groove 20a. When the shank 22a is positioned in the bore 15a the wall of this bore contacts the surface of the shank 22a so that the liquid under pressure flows through the helical groove 28a to the annular groove 20a, and is then sprayed from the nozzle via the indentations 27a. In this arrangement the sprayed liquid leaves the nozzle in a path somewhat axial with respect to the nozzle instead of somewhat laterally, as is the case in the arrangement shown in Figure 1.

One of the main advantages of my new and improved nozzle lies in the fact that the spray

holes are made of minute sizes without involving difficult and expensive drilling to form these openings as has been the common practice in spraying nozzles of the prior art.

Another advantage of my new and improved nozzle lies in the fact that the screw containing the helical passage and the indentations may be removed whenever it is necessary to clean it, and there are no small holes which become stopped up and which usually are difficult to clear extraneous material from when they get stopped up.

Another advantage of my arrangement is that the total area through which the liquid is to be sprayed can be given a considerable value by the simple expedient of increasing their number.

A further advantage of my nozzle lies in the fact that only a minute quantity of liquid is present in the body of the nozzle at all times. The importance of this feature becomes apparent if it is considered that spray nozzles, such as are used in oil burners, oil engines, or diesel engines, are subject to very high temperatures. If, under such circumstances, the heat is not conveyed away from the nozzle at an extremely rapid rate, and the nozzle contains a considerable amount of fuel, which fuel is generally in the nature of a hydrocarbon, there is always a danger that the nozzle will heat the hydrocarbon to a high temperature, thereby causing the formation of a vapor bubble, or bubbles, the pressure of which may cause the fuel to dribble out of the nozzle at moments when no fuel injecting is desired.

Another harmful effect of overheating of the fuel lies in the occurrence of cracking phenomena, accompanied by the formation of tar-like substances, and in case this occurs these substances so created eventually clog up the spray openings, or if they do not completely clog the openings they create the danger of carbon formation in the nozzle openings under continued high temperature conditions.

Due to the fact that the quantity of liquids (fuel, for example), in my nozzle is kept to an almost irreducible minimum, there is very remote chance of the above difficulties occurring in my nozzle. The liquid content in the nozzles remains there only for short periods of time so that even if the temperature of the nozzle is quite high there is very little chance of vapor formation or cracking phenomena occurring as the fuel content in the nozzle is constantly eliminated and replaced by new cold fuel. The period of time, therefore, during which the fuel is contained in the body of the hot nozzle will be extremely short, and will be shorter the closer the fit of the grooved shank in the bore of the nozzle. For instance, on an oil engine or diesel engine an almost ideal condition would exist, if the liquid cubic contents of the nozzle are no greater than the minimum quantity sprayed by the nozzle during operation. In this manner one can be sure that at no time cracking or vaporizing of the fuel in the nozzle would occur, during operation of the engine.

It can be easily seen that it is entirely possible to impart to the liquids sprayed by my nozzle a whirling motion by the simple expedient of giving the indentations a spiraled form instead of a straight one. It seems that this fact is so obvious that I did not deem it necessary to illustrate indentations of this kind.

Although I have herein shown and described one form of my new and improved spray nozzle and modifications thereof, it is obvious that many changes may be made in the arrangements herein

shown and described within the scope of the following claims.

What is claimed is:

1. In a spray nozzle, a body having means thereon for mounting it in use, a longitudinal passage formed within said body, a threaded passage also formed within said body smaller than the diameter of and communicating with said first passage, said threaded passage being near one end of said body, means on said last end of said body for connecting said passages to a source of fluid under pressure, an outwardly facing conical cavity formed in said body at the opposite or discharge end thereof, a stem in said nozzle having a portion threadedly engaging said threaded passage, having a shank portion parallel to and intimately contacting the surface of said bore and having a cone-shaped head the conical surface of which is substantially parallel to and forced in contact with the surface of said conical cavity by the aforesaid threaded engagement, a plurality of diverging grooves formed in at least one of said conical surfaces and forming passages through which said fluid is sprayed angular with respect to the longitudinal axis of said nozzle, and groove means on said stem forming with the wall of said longitudinal passage fixed minute passages via which said fluid passes from said first end to the grooves in said conical surface, thereby insuring that said body contains a minimum of said fluid at all times.

2. In a spray nozzle, a body having a longitudinal passage formed therein from the discharge end thereof, an outwardly facing frustro-conical depression formed in the discharge end of said body, a threaded passage formed within said body and communicating with said first passage, said threaded passage being smaller in diameter than said first passage, a third passage formed within said body and extending inwardly from the inlet end to communicate with said threaded passage, said third passage also being internally threaded to accommodate a fitting via which fluid to be sprayed is delivered thereto, a stem having a shank forming a snug fit with the interior wall of said first passage and having a threaded portion engaging said first mentioned threaded passage, and means to lock the same in engagement with the latter, said stem also having an extension head having an annular angular surface forced into contact with the surface of said depression by the engagement of said threaded portion with said first threaded passage, groove means formed in said surface of said head via

which said fluid is sprayed, spiral groove means formed on the portion of said shank forming said snug fit and providing minute passages through said body for the fluid, and an annular passage formed on said shank adjacent to said head and providing communication between said spiral groove means and said first mentioned groove means, said annular passage having a cross section at least as great as the sum of the cross sections of said spiral groove means.

3. In a spray nozzle, a body having means thereon for mounting it in use, a longitudinal passage formed within said body, a stem mounted in and forming a snug fit with the interior wall of said passage and having a portion thereof threadedly engaging the interior of said nozzle, groove means formed on said stem for the passage of fuel to be sprayed, an outwardly facing frustro-conical depression formed in the discharge end of said nozzle, a head on the end of said stem having a frustro-conical portion, the surface of which mates with and is in forced contact with the surface of said depression by said threaded engagement of said stem portion with the interior of said nozzle, an annular passage formed between said body and said stem adjacent to said head and communicating with said groove means, and a plurality of spaced grooves formed in at least one of said frustro-conical surfaces communicating with said annular groove, the cross sections of said groove means and said annular groove being such that said nozzle contains a minimum of said fuel at all times thereby minimizing the chance of carbonization.
